UNITED STATES PATENT OFFICE.

LOUISE L. WHITTEMORE, OF BOSTON, MASSACHUSETTS.

DESIGN FOR A BADGE.

SPECIFICATION forming part of Design No. 30,304, dated March 7, 1899.

Application filed December 23, 1898. Serial No. 700,174. Term of patent 7 years.

To all whom it may concern:

Be it known that I, LOUISE L. WHITTEMORE, a citizen of the United States, residing at Boston, in the county of Suffolk and State of Massachusetts, have invented and produced a new and original Design for Badges, of which the following is a specification, reference being had to the accompanying drawing, forming part thereof.

10 The figure shows a front view of my new design.

As shown in the drawing, the design consists of a bell A, suspended by links B to a cross-bar C. A pin is secured at the rear of 15 the cross-bar, whereby the badge may be se-

cured to the clothes of the wearer. The bell A has at its lower, upper, and central portion an ornamental belt a, and the cross-bar C terminates in a scroll, as shown at c, and scroll-work is arranged above said bar, as shown at 20 d d d.

Having described my invention, what I claim as new, and desire to secure by Letters Patent, is—

The design for a badge as herein shown and 25 described.

LOUISE L. WHITTEMORE.
